UNITED STATES PATENT OFFICE.

ABBOTT Q. ROSS, OF CINCINNATI, OHIO.

IMPROVEMENT IN MACHINERY FOR DISCHARGING GAS-RETORTS.

Specification forming part of Letters Patent No. **222,563**, dated December 9, 1879; application filed September 8, 1879.

To all whom it may concern:

Be it known that I, ABBOTT Q. ROSS, of Cincinnati, in the county of Hamilton and State of Ohio, have invented certain new and useful Improvements in Machines for Discharging Gas-Retorts, of which the following is a specification.

This invention relates to certain improvements upon a machine for discharging coke from gas-retorts, for which I filed an application for Letters Patent on the 1st day of July, 1879, which application has been allowed, but the patent has not yet issued.

Said improvements consist, first, in making the counter-balance to aid in supporting the rakes, when projected, automatically adjustable, as hereinafter described; second, in providing means for unshipping the mechanism which moves said counter-balance, and fixing the latter immovably on its lever when one rake only is in use, as hereinafter described; and, third, in providing one or more shields to guide the descent of the coke as it is withdrawn from the upper and middle retorts, or either of them, and prevent it from falling upon the rake arm or arms below, or being scattered upon the floor, as hereinafter more fully described.

In the accompanying drawings, Figure 1 is a side elevation of the machine, as seen from the side to which the rake-arms are attached. Fig. 2 is a perspective view of the opposite side of the machine. Fig. 3 is a detail view of the cross-head upon the piston-rod, showing also the pinion with which the rack upon said cross-head engages to actuate the rakes; and Fig. 4 is a front end elevation of the machine, showing the shields upon which the coke falls as it is discharged from the upper and middle retorts.

A is the main frame of the machine, movable back and forth in front of the retorts, so as to bring the rakes in coincidence with any bench of retorts, as desired.

A' and A² are two vertical standards attached to the main frame and forming parts thereof, and a a' are two bars rigidly connecting said standards, and serving as rails on and between which a reciprocating traveler or carriage, B, runs to operate the rakes, as hereinafter more fully described.

C C' C² are the rake-bars pivoted to a vertical bar, E, which is rigidly attached to said reciprocating traveler. Said rake-bars, when in use, are pivoted to the bar E at e e e; but when it is desired to use only one or two of the rakes at the same time, the bars of such as are to remain idle are detached from said bar E and secured to the rigid frame of the machine at any or either of the points e' e' e'.

D is the reciprocating traveler, which runs upon the connecting-bar a on grooved rollers d d, and is guided and held in position by grooved rollers d' running under bar a'.

F is an adjusting-bar, supporting the front ends of the rake-bars, which is secured in suitable guides to the standard A' in such manner that it may be moved vertically up and down to elevate and depress the rakes e e e. The rake-bars are supported upon and move in the grooves of grooved rollers f f f, and are secured in place by idle rollers f' f' f' upon said adjusting-bar F. Said adjusting-bar is moved up and down by means of a T-lever, G, at the rear end of the machine, connected by rods g g with another T-lever, G', at the front end of the machine, which last-mentioned lever is connected with said adjusting-bar by a link, g'. By raising the handle of the lever G the rakes are elevated, and by pressing it down they are depressed.

H is the cylinder of a reciprocating steam-engine which drives the machine, and H' is a hydraulic governor or regulator, the construction and functions of which are fully described in my said pending application, and need not be particularly described here, as it forms no part of my present invention.

The piston-rod I of the steam-cylinder H also works a piston in the governor H', and between said cylinder and governor is a cross-head, J, secured to the piston-rod by a set-screw, and it slides to and fro upon and between two guide-plates, J' J'. On the lower side of said cross-head is a toothed rack, j, which engages with a toothed pinion, i, upon a shaft, i', on the opposite end of which is a drum, K. Around said drum is wound a wire rope or chain, k, one end of which is carried around a grooved roller, i², up and around another grooved roller, i³, thence to the reciprocating traveler, to the central part of which

it is attached, and the other end is carried around a grooved roller, i^1 , thence up and around a grooved roller, i^2 , thence to the reciprocating traveler, to which it is attached opposite the point of attachment of the other end.

As the piston-rod moves to and fro the rack upon the cross-head J revolves the pinion i, which turns the drum I, causing the wire rope or chain to move the traveler to or from the retorts, according to the direction in which the piston-rod moves.

Thus far I have described only so much of my machine as is described and claimed in my said former application. I will now proceed to describe my improvements thereon.

L is a lever, having its fulcrum at l on a bracket, l' , secured to the standard A'. The short end of this lever is connected by a link, l^2 , to the upper end of the adjusting-bar F. On the other end of said lever L is mounted a movable weight or counter-balance, M, having in its upper portion two grooved rollers, m m, which ride upon the lever L, which lever passes through a slot in said weight.

To the forward part of said weight M is attached one end of a rope or chain, n, which passes forward and around a grooved roller, n' , thence back through a hole in the lower part of the weight to the rear end of the lever L, where it passes around another grooved roller, n^2 , thence back to the weight M, to the rear end of which it is attached. The grooved roller n' is mounted on the same shaft with a sprocket-wheel, o, said shaft having its bearings in the bracket l' .

From the cross-head J an arm, P, projects toward the rake-bars, to the outer end of which arm a small cross-head, p, is secured by a set-screw, and to this small cross-head one end of a chain, Q, is attached, which chain passes around a sprocket-wheel, o', mounted on the rigid frame of the machine; thence passes up and around sprocket-wheel o; thence down and around another sprocket-wheel, o²; thence back and around a sprocket-wheel, o³, at the rear end of the machine, and thence to the cross-head p on the arm P, to which it is attached.

It will be seen that as the piston-rod moves toward the retorts, and thus projects the rakes

farther from their bearings upon the adjusting-bar F, it so moves the chain Q as to rotate the sprocket-wheel o and the grooved roller n' , and thus so moves the chain n as to cause it to draw the weight M away from the fulcrum of lever L and give it an increased leverage to support the advanced rakes; and when the piston-rod moves back it, in like manner, draws the weight toward the fulcrum of the lever, and thus diminishes the leverage, as less leverage is required to counterbalance the rakes.

When but one rake is in use, the weight, having been properly adjusted, may be permanently fixed upon the lever L by means of the set-screw t, and the chain Q may be unshipped from the cross-head J by loosening the set-screw which secures the small cross-head p upon the arm P and removing the said cross-head p therefrom. The movement of the piston-rod will not then move the weight.

S S are two shields hinged to the adjusting-bar F, and falling down at an incline upon the middle and lower rake-arms, thus forming scrapers to keep the upper surfaces of the said rake-arms clean, and effectually preventing the coke from falling upon said rake-arms, and from being carried out onto the floor, and from getting between the grooved and idle rollers f and f'.

What I claim as my invention is—

1. In combination with a reciprocating rake or series of rakes, an automatically-adjustable counter-balance, in combination with and actuated by the piston-rod and connecting mechanism, substantially as herein described.
2. In combination with the chain Q, for operating the counter-balance, the small cross-head p, detachable from the arm P, substantially as and for the purpose set forth.

3. In combination with the reciprocating rakes, the inclined shields S S, or either of them, hinged to the adjusting-bar F, substantially as and for the purpose described.

In testimony that I claim the foregoing I have hereunto set my hand in the presence of the subscribing witnesses.

ABBOTT Q. ROSS.
